UNITED STATES PATENT OFFICE.

JOHN H. COOK, OF BROOKLYN, NEW YORK, ASSIGNOR TO GEORGE W.
COOK, OF SPRINGFIELD, MASSACHUSETTS.

PENCIL-SHARPENER.

No. 836,094.

Specification of Letters Patent.

Patented Nov. 20, 1906.

Application filed February 2, 1906. Serial No. 299,132.

To all whom it may concern:

Be it known that I, JOHN H. COOK, a citizen of the United States of America, residing at Brooklyn, in the county of Kings and State 5 of New York, have invented new and useful Improvements in Pencil-Sharpener, of which the following is a specification.

This invention relates to the class of pencil-sharpener; and it has for its object to 10 provide a structure by which the pencil can be quickly and accurately sharpened.

The invention consists in providing a piece of sandpaper or other flexible abrasive material which can be readily attached to and 15 detached from a disk adapted for rotation at a comparatively high speed, and a clamp for readily securing the sandpaper or other abrasive material to the disk, and suitable 20 gearing for rotating the pencil-clamp in an opposite direction to the sandpaper-disk.

In the drawings forming part of this application, Figure 1 is a perspective view of my improved pencil-sharpener. Fig. 2 is a vertical section through the pencil-clamp, bevelled gears, and sandpaper-disk, and adjacent parts, while Fig. 3 is a perspective view of the receptacle for receiving waste material.

Referring to the drawings in detail, *a* designates the main upright casting for receiving 30 the operative parts of the device, which is integral with the base portion *b*.

c designates a shaft which is mounted for rotation in the boss or hub *d* of the upright piece *a*. Secured to the outer end of this 35 shaft *c* is a crank *e*, while on the inner end is a combined bevelled and spur-gear wheel *f*, the the spur-teeth being on the periphery of the wheel and the bevelled teeth being on the inner face thereof, as shown.

40 Meshing with the spur-teeth is a pinion *h*, secured to a stud or shaft in the standard *a* and carrying at its outer end a disk *i*, of metal or other suitable material. The outer rim of this disk has a concave groove *j* therein for 45 the purpose of receiving the divided spring clamping-ring *k* for the purpose of detachably securing a piece of sandpaper *m* or other similar flexible abrasive material, although I preferably use sandpaper. When 50 a piece of the same becomes worn, another piece may be readily substituted therefor by bending the edges of the paper into the groove *j* and snapping the clamping-ring *k* thereon, as clearly shown in Figs. 1 and 2.

The standard *a* has an arm portion *a'* at 55 its top that is substantially at right angles to the upright portion, as shown in Fig. 2, and carries in the outer end thereof a bearing-piece *n*, to which the bevelled gear *o* is secured or may be made integral therewith. 60 This bearing-piece *n* is held in place in the bent arm by means of a screw *p*, engaging a groove *q*, as shown. Located concentric with the axis of the bearing-piece *n* and bevelled gear *o* is the spring pencil-clamp *r*, which is 65 rigidly secured to the parts *n* and *o*. The arm-portion *a'* is inclined downward, so that the axis of the pencil-clamp will intersect the center of the rotating disk *i*, which carries the sandpaper. 70

It will be readily seen that upon the rotation of the crank *e* the pencil *s* will be rotated at a comparatively high speed in one direction, while the sandpaper-disk *i* will be rotated at a comparatively high speed in the 75 opposite direction, thus insuring a relatively great movement between the pencil and sandpaper. The wood of the pencil is therefore quickly worn away and the same brought to a sharp point in a short time. 80

It is to be understood that by the placing of the pencil in the clamp the same is gradually pushed downward by hand as the wood is cut away until the desired degree of sharpness is imparted to the pencil. 85

Located immediately below the sandpaper-disk *i* and inclosing about one-half of the same is a removable receptacle *t* for receiving the waste products. This receptacle has secured to the lower side thereof a foot-piece 90 *u*, having a slot *v* for engaging a screw *w* on the base of the device, thus permitting the receptacle to be readily removed and the waste products emptied. 95

Embraced within the scope of my invention instead of employing the clamping-ring *k* I may simply emboss or crease the edge of the abrading-disk, so that the same can be pushed over the edge of the disk *i*, and thus be held in place in the groove *j* without the use of the clamping-ring. 100

Having thus described my invention, what I claim, and desire to secure by Letters Patent of the United States, is—

1. In a device of the class described, a base-piece, an upright integral therewith and having its top portion bent at an angle to the upright, a disk revolubly mounted in the up- 105

right and having a groove in the periphery thereof, means for securing abrasive material to the face and edge of the disk, said means engaging the groove thereof, a pencil-clamp located in the bent portion of the upright and above the axis of the disk, and means for rotating the pencil-clamp and disk.

2. In a device of the class described, a disk having a groove in the outer edge thereof, a ring for engaging said groove and detachably securing flexible abrasive material thereto, an upright having an arm substantially at right angles thereto and in the same vertical plane as the upright, a rotatable bearing-piece in said arm and above the axis of the disk, a pencil-clamp secured to the bearing-piece, and means for rotating the pencil-clamp and disk in opposite directions, the axis of said pencil-clamp and disk intersecting, and means for operatively connecting the disk and rotatable bearing-piece.

3. In a device of the class described, an upright, an integral arm substantially at right angles to the same, a driving-shaft in said upright, an element having bevel and spur teeth thereon, a beveled gear secured in the bent arm and meshing with the bevel-teeth of said element, a pencil-clamp mounted in said bevel-gear, a pinion meshing with the spur-gear of said element and carrying a disk, said disk having a groove in its outer edge, a spring-clamp adapted to engage said groove and detachably secure a piece of

abrasive material thereto, the axes of the pencil-clamp and disk intersecting the outer 35 surface of the abrasive material.

4. In a device of the class described, an upright, a disk having a concave groove in the periphery thereof and carrying an abrading element, a pinion secured to the disk and 40 rotatably mounted in the upright, a beveled gear and pencil-holder, an element having beveled and spur teeth thereon, the spur-teeth engaging said pinion and the beveled teeth engaging the beveled gear, said beveled 45 gear carrying the pencil-holder, the axis of said pencil-holder intersecting the surface of the abrading element carried by the disk as described.

5. In a pencil-sharpener, a gear having 50 bevel and spur teeth thereon and suitable means for supporting the same, a disk having a circumferential groove and carrying abrasive material, a pencil-holder, a pinion 55 axially arranged with relation to the disk and meshing with the bevel-teeth of said gear, a beveled gear meshing with the bevel-teeth of said gear and carrying the pencil-holder, said pencil-holder adapted for rotation with said bevel-gear, and means for detachably 60 securing the abrasive material in the groove.

JOHN H. COOK.
